APPARATUS FOR MOUNTING RUBBER SLEEVES
ON INNER CORE BARREL TUBES
Benjamin L. Austin, Ogden, and Takeshi Mori, Salt Lake
City, Utah, assignors to Christensen Diamond Products
Company, Salt Lake City, Utah, a corporation of Utah
Filed May 16, 1960, Ser. No. 29,325
16 Claims. (Cl. 29—234)

The present invention relates to core barrels for securing cores from formations in well bores, and more particularly to apparatus for mounting a sleeve of rubber, or similar material, on a tubular member, the rubber sleeve being adapted to receive and retain a core in the well bore as it is being formed.

As shown in the application of Benjamin L. Austin, Serial No. 807,635, filed April 20, 1959, now Patent No. 3,012,622, for "Core Barrel Apparatus," a rubber or rubber-like sleeve is mounted on the exterior of tubing in doubled back or folded and laterally stretched or expanded condition. As the core is formed in the well bore, the rubber sleeve is pulled around the lower end of the tubing and upwardly into its interior to contract laterally around and embrace the core being produced.

An object of the present invention is to provide an apparatus for doubling back or folding an elongate rubber sleeve on itself, so that the sleeve consists of an outer layer surrounding an inner layer, and mounting such doubled back sleeve on the exterior of core barrel tubing in a laterally stretched or expanded condition, the normal or unrestrained diameter of the rubber sleeve being less than the inside diameter of the tubing.

A further object of the invention is to provide an improved apparatus for pulling a rubber or rubber-like sleeve over and along tubing, in which the normal or unrestrained diameter of the sleeve is substantially less than the outside diameter of the tubing. More specifically, the rubber sleeve has previously been doubled back or folded on itself, and such folded sleeve is pulled or stretched comparatively readily over tubing intended to form part of core barrel apparatus, the rubber sleeve also being an important portion of such apparatus.

This invention possesses many other advantages, and has other objects which may be made more clearly apparent from a consideration of a form in which it may be embodied. This form or method is described and shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

FIGURE 1 is a side elevational view of an apparatus embodying the invention;

FIG. 2 is a longitudinal section, parts being shown in side elevation, through a portion of the apparatus disclosed in FIG. 1;

FIG. 3 is an end view of the apparatus taken along the line 3—3 on FIG. 1;

FIG. 4 is an enlarged vertical section taken along the line 4—4 on FIG. 1;

FIG. 5 is a top plan view of a portion of the apparatus used in pulling the rubber sleeve on the core tube;

FIG. 6 is a section taken along the line 6—6 on FIG. 5;

FIG. 7 is a longitudinal section, partly in side elevation, illustrating the first step in doubling back or folding a rubber or rubber-like sleeve on itself;

FIG. 8 is a view similar to FIG. 7, illustrating a subsequent step in the doubling back or folding of the rubber sleeve on itself;

2

FIG. 9 is a longitudinal section through a rubber sleeve as it appears after the doubling back operation has been completed;

FIG. 10 is a longitudinal section, parts being shown in side elevation, of the folded sleeve being placed in position for mounting on the loading device of the apparatus;

FIG. 11 is a view similar to FIG. 10, disclosing the folded sleeve expanded and prior to mounting on the loading device;

FIG. 12 is a view similar to FIG. 10 of the rubber sleeve mounted on the loading device;

FIG. 13 is a longitudinal section of the loading apparatus and the commencement of pulling the doubled back or folded sleeve on the inner tube or barrel of the coring apparatus;

FIG. 14 is a longitudinal section, partly in side elevation and on an enlarged scale, of the double back rubber sleeve being pulled over the inner tubing of the core barrel;

FIG. 15 is a view of the folded rubber sleeve mounted on the tubing of the core barrel;

FIG. 16 is a view similar to FIG. 15 showing the outer layer of the rubber sleeve moved back beyond the end of the core barrel tubing to enable its folding upwardly with-

20 in the tubing.

The drawings illustrate an apparatus that includes a device A for doubling back or folding an elongate rubber sleeve S so that it then constitutes an inner layer 10 integral with an outer layer 11. The apparatus also includes a loading device B for forcibly mounting the folded rubber sleeve onto an appropriate length of tubing T, which has an outside diameter substantially less than the normal or unrestrained diameter of the rubber sleeve itself.

As illustrated, the apparatus includes a frame or stand 35 12 having a set of divergent rear legs 13 and a set of divergent front legs 14, the pair of rear legs being connected to an inverted Y fitting 15, and the pair of front legs to an inverted V-type of fitting 16. Extending between the fittings 15, 16 and suitably secured thereto is an elongate horizontal tube 17.

Secured to the Y fitting 15 at the rear of the stand 12 is the inverter device A for doubling back the rubber sleeve S on itself, so to provide the inner and outer layers 10, 11. This inverter includes a vertical support or base 18 threadedly or otherwise suitably secured to the upper portion of the Y fitting 15, this base being welded, or otherwise suitably secured, to a housing 19 having a rear enlarged portion 20 and a smaller diameter forward portion 21 terminating in a flange 22. The enlarged housing portion 20 has an end wall 23 suitably welded thereto, provided with a transverse horizontal slot 24 therethrough of a size to receive the rubber sleeve S when in a flattened condition. Secured to the exterior of the end wall is a rubber or rubber-like seal disc 25 which is held against the end wall by a plate 26 attached thereto by a plurality of screws 27. This plate has a horizontal slot 28 in alignment with the end wall slot 24, and the rubber seal disc 25 also has a horizontal slot 29 in alignment with the end wall slot 24.

The operation of the inverter A in converting the elongate rubber sleeve S from its initial length to a doubled back condition, possessing the inner and outer plies 10, 11, will be described hereinbelow.

The apparatus also includes the loading device B which is also carried by the stand or frame B of the apparatus. This loading device includes a winch 30 that comprises a suitable housing 31 having end walls 32 and a shaft 33 extending therewithin and through the end walls. Secured to this shaft, as by means of a set screw 34, or the like, is a winding drum 35 on which a suitable length of wire cable 36 is wound. The cable extends a horizontal opening 37 in the housing between its end walls

and its free end is adapted to be secured to a loading mechanism 38, later to be specifically described. The winch housing 31 is suitably secured, as by welding, to a vertical support or brace 39, which is, in turn, welded or otherwise suitably secured to the longitudinal tube 17 of the loading stand 12. The housing 31 is also attached to a horizontally disposed outer body member 40, which is piloted within and is secured, as by welding, to a tubular body 41 having a forward threaded box 42 adapted to receive the rear threaded pin portion 43 of a support sleeve 44 on which the core barrel tubing T is adapted to be mounted when the rubber sleeve S is to be pulled thereon, as later described. This tubular support sleeve 44 can be threaded into the box portion 42 of the body 41, or unthreaded therefrom, by placing a suitable rod or tool (not shown) in one of the radial holes 45 in the sleeve.

The body of the apparatus, including the outer body portion 40, forms a portion of a mechanism for stretching the doubled over rubber sleeve S and for obtaining its mounting on the loading mechanism 38. This stretching mechanism includes a central support rod 46, the rear end of which is threaded into the outer body member 40, and having an air passage 47 communicating with an air passage 48 in the outer body member that leads into a side port 49 in which an air valve 50 is threaded, so that an air line L (FIGS. 10-12) can be attached to the valve in order to force air under pressure into the passage 49, 48, 47.

Mounted on the rod 46 is a loading balloon 51, the ends of which are secured to the rod. As shown, the rear end of the rubber or rubber-like loading balloon 51 has an enlarged wall thickness 52 extending rearwardly of a rod flange 53, the thickened portion being disposed between the inner wall of the body 41 and the periphery of the rod. The forward end of the loading balloon also has an inwardly directed flange portion 54 to provide a substantially greater wall thickness than the main length of the loading balloon, this flange being disposed forwardly of an external rod flange 55, the forward end of the loading balloon being prevented from removal from the rod by an encompassing holding cup 56 held in position on the rod by a suitable screw 57 threaded into the rod and engaging the end of the holding cup.

A lateral port 58 extends from the central air passage 47 of the rod to the interior of the loading balloon 51 between the flanges 53, 55, such that air under pressure can pass from a suitable supply through the valve or fitting 50 and into the air passages 49, 48, 47 and out through the port 58 to the interior of the loading balloon, to inflate the latter and cause a lateral stretching of substantial enlargement in diameter of the doubled over end of the rubber sleeve S, as hereinbelow explained.

When the loading balloon 51 is to be inflated in stretching the rubber sleeve, the support sleeve 44 is unthreaded from the body 41 and is removed completely therefrom, being placed to one side. The loading mechanism 38 is adapted to be slipped over the body member 41, and preferably makes a sliding fit thereon. The loading mechanism includes a tubular housing 59 having an external flange 60 at its forward end and an enlarged housing portion 61 at its rear end provided with a lateral port 62 in which an air inlet fitting 63 is secured, which is adapted to be connected to a suitable source of air pressure. The loading housing 59 is adapted to be slipped over the core barrel tube T and sealed against the periphery of the latter by means of an annular seal member or ring 64 secured to the loading flange by a holding ring 65 held in place by screws 66. When the housing is slipped over the tube T, the seal ring 64 will fold in an outward direction within the counterbore 67 of the housing 59, the inside diameter of the seal ring then being substantially equal to the external diameter of the tube T.

The loading mechanism 38, when mounted on the body

41, is adapted to be moved in a forward direction under the inflated or stretched doubled back portion of the rubber sleeve S. The mechanism is forced under the rubber sleeve by means of a crank and connecting rod device 5 actuated from the winch 30. Thus, one or a plurality of crank discs 68 are secured to the winch shaft 33 externally of the housing 31, each crank disc having a crank pin 69 thereon adapted to receive the end of a connecting rod or link 70 pivotally mounted on a hinge pin 71 secured to the loading housing 59. The rear portion of the link has a coupling slot 72 to permit ready connection and disconnection of the link to its companion crank pin 69. When the links are connected to the crank pins, the loading device 38 may be moved forwardly on the body 41 by applying turning effort or torque to one of the actuating arms 73 of the winch mechanism, which is slidably secured to a hub 74 fastened on the shaft 33. This same actuating mechanism is used in winding the cable 36 on the winding drum 35. The forward end of the cable 36 is attached 10 to a bracket 75, as through use of a screw 76, the bracket being welded to one of the links or connecting rods 70 pivoted to the loading housing 59.

In the operation of the apparatus in folding back a rubber sleeve S on itself, and then mounting it in a laterally stretched condition on the core tubing T, a suitable 15 length of the rubber sleeve, which may, for example, be about twenty feet in length, is first provided, and one of its ends is flattened and forced manually through the aligned slots 28, 29, 24 in the plate 26, seal disc 25 and 20 end wall 23, the rubber sleeve projecting forwardly from the inverter housing 19, and then being manually doubled back upon themselves so as to fit upon the smaller diameter portion 21 of the housing, as shown in FIG. 7. When 25 in this position it will be noted that the seal disc 25 seals against the exterior of the rubber sleeve, which, 30 of course, is in a flattened condition in the region of the horizontal slots.

A loading sock N of a suitable length, which may be 35 made of nylon, is then disposed over the doubled back 40 end portion of the rubber sleeve, the doubled back end of the sleeve then being clamped to this portion 21 by 45 means of a clamp or strap C which may be of any suitable type, the flange 22 of the housing preventing forward removal of the end portion of the sleeve S from the inverter 50 housing 19. An air line L is then connected to an 55 inverter fitting 80 and air under suitable pressure fed through the line into the inverter housing 19. Air is only permitted to enter the housing at a relatively slow 60 rate, the air pressure forcing the rubber sleeve S in a forward direction within the nylon sock N and pulling it 65 through the horizontal slots 28, 29, 24 (FIG. 8). During the pulling of the rubber sleeve through the slots, the outside of the rubber sleeve may have light engine oil applied thereto. Air is fed into the housing until the 70 rubber sleeve has been almost completely doubled back 75 upon itself and with a rear end E of the sleeve, of a short length, still extending from the end plate 26, as for example, one inch short of such plate. The air is then bled from the inside of the housing 19 and the sleeve S. The nylon sock N is then removed, the clamp C 80 loosened, and the sleeve pulled off the smaller diameter portion 21 of the housing and its inner layer 10 pulled completely through the inverter, the sleeve then being in the condition illustrated in FIG. 9.

The loading mechanism 38 is then slipped over the 85 body 41 and its links 70 connected to the winch crank pins 69, the folded end F of the sleeve S then being disposed over the loading balloon in the position disclosed in FIG. 10, in which the end of the sleeve is 90 approximately flush with the end of the loading device 38. The air supply line L is then snapped on the air fitting 50 and air under pressure allowed to flow through the passages 49, 48, 47, 58 into the interior 95 of the loading balloon 51, the balloon inflating and stretching the inner and outer plies 10, 11 of rubber out-

wardly until the diameter of the end portion F of the sleeve is approximately the same size as the tapered tip 69 of the loading device, or slightly larger in diameter (FIG. 11). The winch handles 73 are then turned so that the crank pins 69 force the links 70 and the loading device 38 in a forward direction, the loading device sliding forwardly on the body 41 and its flanged tip 69 being forced between the rubber sleeve S and the loading balloon 51 until the entire forward portion of the housing 59 is disposed within the sleeve S, as shown in FIG. 12. To facilitate forcing of the loading device housing 59 between the loading balloon 51 and the rubber sleeve S, a small amount of lubricant might be first placed on the tapered flange tip 69. The air is then exhausted from the loading balloon 51 which will then return inherently to its initial contracted condition. The hook portions 72 of the connecting rods 70 are then detached from the crank pins 69 and the loading device 38 then pulled in a forward direction completely off the body 41 of the apparatus.

The clamp C is then placed on the rubber sleeve S to clamp it securely to the loading housing 59, and the housing 59, with the doubled back rubber sleeve S thereon, placed on to one side of the apparatus.

The support sleeve 44 is then mounted over the loading balloon 51 and is threaded into the box 42 of the body 41. The inner tubing or barrel T of the coring apparatus is then slipped over the support sleeve 44, as shown in FIGS. 13, and 14, and the cable 36 unwound from the winch drum 35 until the loading device 38 is a little beyond the forward flanged end 90 of the tubing remote from the support sleeve 44. A substantial quantity of lubricating oil, such as a pint, is then preferably poured inside of the loading device 38, flowing down inside the inner ply 10 of the rubber sleeve to assist in the pulling of the rubber sleeve over the tubing T. When this action has been accomplished, the loading flange 38 is pushed over the forward end 90 of the inner tube T, and the handles 73 actuated to turn the winding drum 35 and pull on the cable 36, which will then pull the loading device 38 and the rubber sleeve S onto the tube T. The nylon loading sock N is then placed over the outside of the rubber sleeve S and pulled up as far as possible on the portion F of the rubber sleeve stretched over the end of the loading device 38 (FIG. 13). The air supply line L is then snapped onto the fitting 63 to feed air into the loading device 38 and also into the doubled over sleeve S. Preferably, the air is turned on in full volume. The rubber sleeve S is then pulled over the tubing T by turning the winch handles 73 and reeling in the cable 36, the air supply acting on the seal member 64 (which slidably seals against the tube T) and assisting in pushing the loading device 38 and the rubber sleeve S in a rearward direction along the tubing T. The air is retained in the rubber sleeve S and the cable 36 reeled in until the inner layer 10 of the rubber sleeve moves past the flange 90 on the end of the tubing T. The air supply is now turned off, the nylon sock N removed, the clamp C loosened and the loading clamp 38 pulled out from underneath the rubber sleeve S, which is now mounted on the tubing T within the end E of its inner layer 10 shouldering against the flange 90 of the tubing, and with the end of the outer layer 11 disposed a short distance away from the tubing flange 90 (FIG. 15).

A suitable lubricant or grease is then forced between the inner and outer layers 10, 11 of the sleeve S. A suitable tube (not shown) is forced between the layers 10, 11 and a grease gun applied to the tube, forcing grease between the layers, the outer layer being suitably manipulated as by use of a squeegee to effect distribution of the grease completely around and between the layers, and up to the return end F of the rubber sleeve. The lubricant is provided to effect a slight separation between the inner and outer layers 10, 11 so

they will not adhere to one another. The outer layer 11 of rubber is then moved by hand along the inner layer 10 until it is disposed longitudinally outwardly beyond the flanged end 90 of the tubing, the extended projection beyond the end of the tubing T being, by way of example, about 3 inches (such as shown in FIG. 16).

The tubing T loaded with the folded over rubber sleeve S may now be assembled in the core barrel apparatus, as shown in the above-identified application, with the projecting end G of the outer layer 11 disposed within the tubing T and secured to parts within the tubing T.

We claim:

1. In apparatus for mounting a pliant, elastic sleeve on a tubular member after the sleeve has been doubled back on itself: a tubular loading device; means for expanding the doubled end portion of the sleeve; means for forcing said loading device into the expanded doubled end portion of said sleeve; means for supporting the tubular member; means comprising a portion of said forcing means for moving said device and sleeve mounted thereon over and along the tubular member to mount the sleeve on the tubular member and means for feeding fluid under pressure through said device into the space between the tubular member and said device and the sleeve while said device is being pulled along the tubular member.

2. In apparatus for mounting a pliant, elastic sleeve on a tubular member after the sleeve has been doubled back on itself: a tubular loading device; means for expanding the doubled end portion of the sleeve; means for forcing said loading device into the expanded doubled end portion of said sleeve; means for supporting the tubular member; means comprising a portion of said forcing means for moving said device and sleeve mounted thereon over and along the tubular member to mount the sleeve on the tubular member; seal means on said device for slidably sealing against the periphery of the tubular member; and means for feeding fluid under pressure through said device into the space between the tubular member and said device and the sleeve while said device is being pulled along the tubular member.

3. In apparatus for mounting a pliant, elastic sleeve that has been doubled back on itself on a tubular member: a supporting member; an inflatable balloon carried by said supporting member and over which the doubled end portion of the sleeve can be disposed; means for feeding fluid under pressure into said balloon to inflate the same and expand said end portion of the sleeve; a tubular loading device on said supporting member; means for forcing said device over said balloon and into said expanded end portion in the sleeve to hold the end portion in expanded condition; means for supporting the tubular member; and means comprising a portion of said forcing means for moving said device and sleeve mounted thereon over and along the tubular member to mount the sleeve on the tubular member.

4. In apparatus for mounting a pliant, elastic sleeve that has been doubled back on itself on a tubular member: a supporting member; an inflatable balloon carried by said supporting member and over which the doubled end portion of the sleeve can be disposed; means for feeding fluid under pressure into said balloon to inflate the same and expand said end portion of the sleeve; a tubular loading device on said supporting member; means for forcing said device over said balloon and into said expanded end portion in the sleeve to hold the end portion in expanded condition; means on said supporting member for supporting the tubular member; a winding drum; a cable on said drum and attached to the device; and means comprising a portion of said forcing means for rotating said drum to wind the cable thereon and pull said device and sleeve mounted thereon over and along the tubular member to mount the sleeve on the tubular member.

5. In apparatus for mounting a pliant, elastic sleeve that has been doubled back on itself on a tubular member: a supporting member; an inflatable balloon carried by

said supporting member and over which the doubled end portion of the sleeve can be disposed; means for feeding fluid under pressure into said balloon to inflate the same and expand said end portion of the sleeve; a tubular loading device on said supporting member; a crank mechanism; link means connecting said mechanism to said loading device, whereby turning of said mechanism forces said device over said balloon and into said expanded end portion of the sleeve to hold the end portion in expanded condition; means for supporting the tubular member; and means comprising a portion of said crank mechanism for moving said device and sleeve mounted thereon over and along the tubular member to mount the sleeve on the tubular member.

6. In apparatus for mounting a pliant, elastic sleeve that has been doubled back on itself on a tubular member: a supporting member; an inflatable balloon carried by said supporting member and over which the doubled end portion of the sleeve can be disposed; means for feeding fluid under pressure into said balloon to inflate the same and expand said end portion of the sleeve; a tubular loading device on said supporting member; a crank mechanism; link means connecting said mechanism to said loading device, whereby turning of said mechanism forces said device over said balloon and into said expanded end portion of the sleeve to hold the end portion in expanded condition; means for supporting the tubular member; a winding drum; a cable on said drum and attached to the device; and means comprising a portion of said crank mechanism for rotating said drum to wind the cable thereon and pull said device and sleeve mounted thereon over and along the tubular member to mount the sleeve on the tubular member.

7. In apparatus for mounting a pliant, elastic sleeve that has been doubled back on itself on a tubular member: a supporting member; an inflatable balloon carried by said supporting member and over which the doubled end portion of the sleeve can be disposed; means for feeding fluid under pressure into said balloon to inflate the same and expand said end portion of the sleeve; a tubular loading device on said supporting member; winding means; crank means on said winding means; link means connecting said crank means to said loading device, whereby turning of said winding means forces said device over said balloon and into said expanded end portion of the sleeve to hold the end portion in expanded condition; means for supporting the tubular member; a cable on said winding means and attached to the device; and means for rotating said winding means to wind the cable thereon and pull said device and sleeve mounted thereon over and along the tubular member to mount the sleeve on the tubular member.

8. In apparatus for mounting a pliant, elastic sleeve on a tubular member after the sleeve has been doubled back on itself: a tubular loading device; fluid pressure operated means for expanding the doubled end portion of the sleeve; means for feeding fluid under pressure to said fluid pressure operated means; means for forcing said loading device into the expanded doubled end portion of said sleeve; means for supporting the tubular member; and means comprising a portion of said forcing means for moving said device and sleeve mounted thereon over and along the tubular member to mount the sleeve on the tubular member.

9. In apparatus for mounting a pliant, elastic sleeve on a tubular member after the sleeve has been doubled back on itself: a tubular loading device; fluid pressure operated means for expanding the doubled end portion of the sleeve; means for feeding fluid under pressure to said fluid pressure operated means; means for forcing said loading device into the expanded doubled end portion of said sleeve; means for supporting the tubular member; means comprising a portion of said forcing means for moving said device and sleeve mounted thereon over and along the tubular member to mount the sleeve on the tubular member.

5 8 sleeve on the tubular member; and means for feeding fluid under pressure through said device into the space between the tubular member and said device and the sleeve while said device is being pulled along the tubular member.

attached to the device; and means for rotating said winding means to wind the cable thereon and pull said device and sleeve mounted thereon over and along the tubular member to mount the sleeve on the tubular member.

14. In apparatus for expanding a pliant, elastic sleeve and for holding the sleeve in expanded condition: a tubular loading device; fluid pressure operated expandible means adapted to be disposed within the end portion of the sleeve to expand such end portion; means for feeding fluid under pressure to said fluid pressure operated expandible means to cause said fluid pressure operated expandible means to expand the end portion of the sleeve; and means for forcing said loading device along said fluid pressure operated expandible means and into the expanded end portion of the sleeve while said fluid pressure operated means is subject to fluid under pressure.

15. In apparatus for expanding a pliant, elastic sleeve and for holding the sleeve in expanded condition: a supporting member; an inflatable balloon carried by said supporting member and over which the end portion of the sleeve can be disposed; means for feeding fluid under pressure into said balloon to inflate the same and expand said end portion of the sleeve; a tubular loading device on said supporting member; and means for forcing said device over said balloon and into said expanded end portion of the sleeve to hold the end portion in expanded condition.

16. In apparatus for expanding a pliant, elastic sleeve and for holding the sleeve in expanded condition: a supporting member; an inflatable balloon carried by said sup-

porting member and over which the end portion of the sleeve can be disposed; means for feeding fluid under pressure into said balloon to inflate the same and expand said end portion of the sleeve; a tubular loading device on said supporting member; a crank mechanism; and link means connecting said mechanism to said loading device, whereby turning of said mechanism forces said device over said balloon and into said expanded end portion of the sleeve to hold the end portion in expanded condition.
